US00D822025S

(12) **United States Design Patent** (10) Patent No.: **US D822,025 S**
Kim et al. (45) Date of Patent: ** Jul. 3, 2018

(54) **INPUT DEVICE FOR AN ELECTRONIC TABLET**

(71) Applicant: **Microsoft Corporation**, Redmond, WA (US)

(72) Inventors: **Young Soo Kim**, Seattle, WA (US); **Mike F. Deily**, Redmond, WA (US); **James Iming Tsai**, Redmond, WA (US); **Ralf Groene**, Kirkland, WA (US); **Hua Wang**, Sammamish, WA (US); **Anthony Reed**, Bellevue, WA (US); **James Alec Ishihara**, Bellevue, WA (US)

(73) Assignee: **Microsoft Corporation**, Redmond, WA (US)

(**) Term: **15 Years**

(21) Appl. No.: **29/616,378**

(22) Filed: **Sep. 6, 2017**

Related U.S. Application Data

(62) Division of application No. 29/557,963, filed on Mar. 14, 2016, now Pat. No. Des. 799,485, which is a division of application No. 29/458,016, filed on Jun. 14, 2013, now Pat. No. Des. 751,553.

(57) **CLAIM**

The ornamental design for an input device for an electronic tablet, as shown and described.

DESCRIPTION

FIG. 1 is a top isometric view of the input device for an electronic tablet showing our new design;

FIG. 2 is a top side view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken line showing of various features of the input device for an electronic tablet is for environmental purposes only and forms no part of the claimed design.

1 Claim, 4 Drawing Sheets
